UNITED STATES PATENT OFFICE.

CHARLES T. BROWN AND FRED W. LEUTHESSER, OF CHICAGO, ILLINOIS,
ASSIGNORS TO MONASH-YOUNKER CO., OF SAME PLACE.

STEAM-TRAP.

SPECIFICATION forming part of Letters Patent No. 679,826, dated August 6, 1901.

Application filed May 10, 1901. Serial No. 59,587. (No model.)

To all whom it may concern:

Be it known that we, CHARLES T. BROWN and FRED W. LEUTHESSER, citizens of the United States, and residents of the city of Chicago, in the county of Cook and State of Illinois, have invented certain new and useful Improvements in Steam-Traps, of which the following, when taken in connection with the drawings accompanying and forming a part hereof, is a full and complete description, sufficient to enable those skilled in the art to which it appertains to understand, make, and use the same.

The object of this invention is to obtain a steam-trap which shall be efficient in operation, sightly in appearance, economical in material and in construction, not liable to leakage at the joining of the parts forming the casing or shell, easily adjusted, and not liable to get out of adjustment in use, the working parts readily exposed to view when the trap is connected up without disturbing the pipe connections thereof, and easily put into operative position and connected up to the steam-pipes of the system to which it is attached.

In the drawings referred to as forming a part of this specification, Figure 1 is a perspective view of a steam-trap embodying our invention. Fig. 2 is an end elevation thereof. Fig. 3 is a vertical longitudinal sectional view; and Fig. 4 is a top plan view of the bottom half of the shell or casing with the operative parts of the steam-trap connected up ready for use, the top half of such shell or casing having been removed to expose such operative parts to view.

A reference-letter applied to designate a given part is used to indicate such part throughout the several figures of the drawings wherever the same appears.

A is the bottom part of the shell or casing of the steam-trap embodying our invention and is bowl-shaped, having a cylindrical body and rounded ends B B.

A' is the top part of the shell or casing and is similar in shape to part A thereof.

B' B' are the rounded ends of the part A' of the shell or casing.

C is an oval peripheral flange extending entirely around part A of the shell or casing,

at the upper edge thereof, and forms the meeting face to flange C' on part A', such flange C' also being oval and extending entirely around the part A'. 55

D D are bolts provided with nuts d d d, respectively, such bolts securing the parts A A' firmly together, and d' is packing interposed between flanges C C' of parts A A'.

E is a projecting lug or body at one end of part A of the shell or casing, and F is a screw-threaded aperture extending through such projecting lug into the interior of the shell or casing, forming the inlet of the steam-trap, into which aperture a steam-pipe connection 60 having corresponding screw-threads is connected from the steam-pipe system designed to be relieved of water of condensation by the steam-trap.

G is a projecting lug or body at the opposite end of the part A of the shell or casing, and H is a screw-threaded aperture therein forming the outlet of the steam-trap, into which aperture a waste - pipe with corresponding screw-threads is to be fitted when 75 the apparatus is connected up for operation in the ordinary way of making the waste-pipe connection.

I is a valve seating to close by-pass I'. (See Fig. 3.) 80

I² is a well forming a passage-way connecting at its lower end with the passage-way I³. Passage-way I³ and well I² constitute the by-pass I', connecting at one end thereof with the interior of the shell or casing of the steam-trap and at the other end thereof with the outlet H and provided with the valve I to close such by-pass when such valve is seated. 85

I⁴ is an ordinary stuffing-box on the stem of valve I. 90

J is a hand-wheel on the valve I.

K is a return-bend attached at one end thereof to the part A of the shell or casing and communicating with the outlet H thereof, (see Fig. 3,) and L is a valve-seat adjustably attached, as by the screw-threads ll, to the end of the return-bend K over the open float N, hereinafter described. 95

M M' are posts, preferably made integral with the part A of the shell or casing of the steam-trap and serving as the supports of the open float N, such open float being provided

with the lugs n n , through which lugs and through which supports M M the rod O is extended, so that the open float N is fulcrumed thereon in a manner permitting upward and downward movement thereof in the shell or casing. Float N is of less weight than the water displaced thereby when no water is contained in the float, and when water of condensation is contained in the float N such 5 float, together with such water of condensation, is of greater weight than the water surrounding the float displaced thereby, and therefore when no water, or but little, is in the float the same is raised by the water surrounding it, and when such float is filled, or 10 nearly so, with water of condensation the float falls or sinks into the water surrounding it.

P is a valve-stem loosely attached at its lower 20 end to the float N and provided at its upper end with the valve R, arranged to seat on the valve-seat L to close the same. We prefer to attach the valve-stem P to float N by pivot Q.

S is a tube or nipple attached at its upper 25 end to the cap i, and such cap i is attached to the valve-seat L by screw-threads corresponding with the screw-threads l l. Tube or nipple S extends at the lower end thereof to near the bottom of float N, so that when 30 such float N is depressed (with water of condensation therein) and valve R thereby unseated the water of condensation contained in such open float N will all, or nearly all, be forced from the steam-trap through such tube 35 or nipple, the valve-seat, return-bend, and outlet H.

The lug or body G at one end of part A of the shell or casing of the steam-trap may be cut away, so as to be limited in size, as is indicated by the broken lines g g of Fig. 1 of the drawings, and in practice we usually do construct the apparatus with such lug or body G so cut away, making it of the shape and appearance illustrated in Fig. 3 of the 45 drawings, although we have constructed them with the lug or body of the shape and size illustrated by the full lines in Fig. 1 of the drawings.

The operation of the steam-trap embodying our invention is as follows: Steam and water of condensation entering the shell or casing of the trap from the pipes to which it is attached through the inlet F the float N is raised, and valve R is seated to close valve-seat L. The contents of the steam-trap are held in the shell or casing by such closing of such valve on its seat. When sufficient water of condensation flows into the shell of the steam-trap to rise therein above the upper 55 edges of float N and fill or nearly fill such float, it will descend in the water surrounding it, and the valve R is unseated from seat L and the water of condensation contained in the float is forced from the shell or casing 60 through the tube or nipple S, valve-seat L, return-bend K, and outlet H. Nearly all the water of condensation in the float N will be

forced from the steam-trap provided the weight of water displaced by the empty float N is of nearly the same weight as is such 70 empty float, and the shell or case of the steam-trap is made of two parts, each bowl-shaped and joined together at the largest part or top of such bowls, as hereinbefore described, as when sufficient water of condensation has 75 flowed over the top of the float N to cause such float to commence to descend it will continue to descend, as the water surrounding such float will flow thereinto as fast as water is discharged therefrom until the float has 80 reached its lowest position and thereafter until the float is nearly empty. As the float descends it more nearly reaches from side to side of the interior of the steam-trap, and but little water will be left in the shell or 85 case outside of the float at the time the float rises into position to close the valve R on its seat. After the float has been emptied of the water of condensation contained therein, as last above-described, it will rise to its initial 90 position, closing the valve on its seat, and thereafter the operation will be repeated at intervals as often as the accumulation of water of condensation collected in the steam-trap is sufficient to flow over the upper edges 95 of the float N, as described.

When it is desired to empty the shell or case of the steam-trap of the contents, whether water of condensation or steam, the same can be done by opening the valve I, thereby opening the by-pass I'.

It will be observed that by constructing the shell or case A A' in the manner described, with the longitudinally-extending flanges C C' at the meeting edges of the bowl-shaped 105 parts of the shell, the holes d² d², through which the bolts D D extend, may be cast and at a uniform distance from each other, notwithstanding the lugs or bodies E and G, and that the inlet F, outlet H, and by-pass I' may 110 also be readily cast by the use of a core-print in the ordinary way, and but little labor is required to finish and assemble the several working parts, and, furthermore, that by placing such flanges C C' as shown room is 115 obtained to place the nuts upon an ordinary bolt D, placed in such holes d² d². By putting packing material between the flanges C C' a water-tight joint is easily obtained.

By making the part A of the shell or casing bowl-shaped, as shown, with the flange C at the upper edge thereof, and adopting a like construction in part A' of such shell or casing we are able to remove the nuts from the bolts at all times and remove the top part 125 A' of the shell without raising part A or moving it from its given position, and when the top part of the shell is removed the working parts of the steam-trap are exposed to view in a manner in which they can be inspected 130 and adjusted.

The upper end of the well I² is preferably placed to discharge into the outlet H to one side of the discharge into such outlet of the

return-bend K, so that when the by-pass is used water flowing upward through well I² and passing out of the outlet H will not flow directly into such return-bend K, as it may 5 occur that (as for purposes of cleaning out the shell or case of the steam-trap) it is desired to blow steam from the shell or casing through the by-pass, in which case there being no water or condensation in such shell or 10 case, or but little thereof, the float N will be in its depressed position, with the valve R off of its seat, and hence an opening through the tube or nipple S, valve-seat L, and the return-bend K to the outlet H, and we do not 15 wish in such case to have the steam so flowing into the outlet H from the well I² and return-bend K to be directed against each other; and it is to obtain the above-recited relative position of the discharge end of the 20 return-bend K and the discharge end of the passage-way I² of the by-pass I into the outlet H that the post M' is cast integral with the end wall of part A of the shell or casing of the steam-trap, as illustrated in Figs. 3 25 and 4 of the drawings. The posts M M are preferably cast integral with post M', but extending above such post M', as illustrated in the drawings. Pivots O O may extend entirely across from one of the posts M M to 30 the other thereof, as is indicated by the broken lines lettered O O in Fig. 4 of the drawings.

Having thus described our invention, what we claim as new, and desire to secure by Letters Patent of the United States, is—

35 1. In a steam-trap the combination of a shell or casing cylindrical in vertical section and provided with circular ends, and consisting of two parts respectively provided with peripheral flanges extending horizontally 40 around the meeting edges thereof, the ends of the lower one of such parts provided with projecting bodies adjacent to the flange thereof, with the inlet and the outlet of the steam-trap extending through such bodies, respectively, and the outlet end of such lower part 45 also provided with a horizontal aperture and a vertical passage-way communicating with such horizontal aperture and with the outlet, a valve in the horizontal aperture arranged 50 to seat to close communication from the interior of the shell to the outlet, a return-bend in the shell, a valve-seat attached to one end of the return-bend, the other end of the return-bend attached to the shell and communicating with the outlet, an open float pivotally attached at one of its ends to the shell, a valve-stem loosely attached at its lower end to the bottom of the float, and at its upper 55 end passing through the valve-seat, a valve 60 at the upper end of the valve-stem and a tube extending from the valve-seat to near the bottom of the float; substantially as described.

2. In a steam-trap, a shell comprising a lower and an upper part, forming, respectively, a bowl and an inverted bowl, both of such parts provided with a horizontally-extending peripheral flange at the meeting edges

thereof, bolts through such flanges securing such parts together, the lower one of such parts provided with an inlet at one end and 70 an outlet at the other end and provided in the inlet-end wall with passage-ways communicating with the outlet and with the interior of the shell, constituting a by-pass and a valve to close such by-pass, in combination with a 75 return-bend attached at one end thereof to the lower part of the shell and communicating with the outlet, a valve-seat at the other end of the return-bend adjustably attached thereto, a float open at its upper end and pivotally attached at one end thereof to the lower part of the shell, a tube from the adjustable valve-seat to near the bottom of the float, a valve-stem loosely attached to the float and a valve on the stem arranged to 80 seat to close the valve-seat when the float is raised; substantially as described.

3. In a steam-trap, a shell comprising a lower and an upper part respectively forming a bowl and an inverted bowl, both of 90 such parts provided with a horizontally-extending peripheral flange at the meeting edges thereof, projecting bodies on the ends of the lower part adjacent to the flange a vertical post within the lower part adjacent 95 to one end thereof and integral therewith, such lower part provided with an inlet through the projecting body at one end thereof and provided with an outlet through the projecting body and post at the other end thereof 100 and provided with a by-pass communicating with the interior of the shell near the bottom thereof and with the outlet substantially midway thereof, a valve to the by-pass a return-bend attached to the post and communicating with the outlet near the inner end thereof, an open float, lugs on one end of the open float, a pivotal connection between such lugs and the post, a valve-seat attached to the inner end of the return-bend, such valve-seat provided with a passage-way extending to near the bottom of the open float, a valve-stem attached to the bottom of the open float and extending through the valve-seat and a valve on such stem seating to close such valve- 115 seat; substantially as described.

4. In a steam-trap, a shell comprising a lower and an upper part respectively forming a bowl and an inverted bowl, both of such parts provided with a horizontally-extending peripheral flange at the meeting edges thereof, projecting bodies on the ends of the lower part adjacent to the flange, a vertical post within the lower part adjacent to one end thereof and integral therewith, 120 such lower part provided with an inlet through the projecting body at one end thereof and provided with an outlet through the projecting body and post at the other end thereof and provided with a by-pass communicating 125 with the interior of the shell near the bottom thereof and with the outlet substantially midway thereof, a valve to the by-pass, a return-bend attached to the post and commu-

nicating with the outlet near the inner end thereof, a valve at the inner end of such return-bend and means to automatically open such valve to discharge water of condensation from the steam-trap to the return-bend and outlet thereof and to automatically close such valve after the discharge of such water of condensation substantially as described.

Signed at Chicago, Cook county, Illinois,
this 8th day of May, A. D. 1901.

CHARLES T. BROWN.
FRED W. LEUTHESSER.

In presence of—
THOMAS H. SMITH,
K. GILLIGAN.
